(57) **CLAIM**

We claim the ornamental design for an aerosol generator cartomizer, as shown and described.

DESCRIPTION

FIG. 1 is a front top perspective view of an aerosol generator cartomizer.

FIG. 2 is a rear bottom perspective view of the aerosol generator cartomizer depicted in FIG. 1.

FIG. 3 is a front elevational view of the aerosol generator cartomizer depicted in FIG. 1.

FIG. 4 is a rear elevational view of the aerosol generator cartomizer depicted in FIG. 1.

FIG. 5 is a right side elevational view of the aerosol generator cartomizer depicted in FIG. 1, the left side elevational view being a mirror image thereof.

FIG. 6 is a top plan view of the aerosol generator cartomizer depicted in FIG. 1; and,

FIG. 7 is a bottom plan view of the aerosol generator cartomizer depicted in FIG. 1.

The broken lines in the drawings illustrate portions of the aerosol generator cartomizer that form no part of the claimed design.
